UNITED STATES PATENT OFFICE.

JOSEPH R. THONET, OF READING, MASSACHUSETTS, ASSIGNOR TO SPRAGUE-HATHAWAY COMPANY, A CORPORATION OF MAINE.

PLATE-SINKING DIE.

Application filed October 20, 1925. Serial No. 63,777.

My invention consists of an improved plate sinking die, the object of which is to provide a simple and economical device for use in embossing cards, photographs and the like.

In the accompanying drawing illustrating my invention, Fig. 1 is a plan view, and Fig. 2 a vertical transverse section on line X—X of Fig. 1.

10 Referring to the drawing, 3 is a thin sheet of material, preferably celluloid, although glass or any other transparent material will be suitable for the purpose. The sheet 3 of transparent material is secured at 15 one edge to a rectangular frame 6 made of a thin sheet of cardboard, or any other suitable material. A rectangular opening 4, shown in dotted lines, is cut out of the frame 6. Secured to the under side of the trans- 20 parent sheet 3 is a sheet 7 of transparent material, preferably made of celluloid or of the same material as the transparent sheet 3. The sheets 7 and 3 may be secured together by lacquer or any cement that does not interfere with the transparency of the two sheets. 25 The sheet 7 is of the same size as the opening 4 in the frame 6 and fits snugly therein when the sheet 3 lies in close contact with the frame 6, allowing space to accommodate the thickness of the paper. 30 5, 5 are eyelets by which the sheet 3 and the frame 6 are secured together at one end, but by reason of the elasticity of the materials of which the sheet 3 and the frame 6 are made, they are 35 readily separable throughout the remainder of their length so that a photograph or other card to be embossed may be inserted between them. While I prefer to eyelet the sheet 3 and frame 6 together, other means, of 40 course, may be used for connecting them without departing from my invention.

In operating the device of my invention, a card to be embossed having been inserted between the sheet 3 and frame 6, sufficient

pressure by a hand or power press is applied to force the sheet 7 down into the space 4 in the frame 6, and thereby to sink the photograph or other card with it into that space, and thereby form a raised margin around the photograph or card to give 45 an attractive effect.

It is obvious that the opening 4 in the frame 6 may be made circular, oval or of any desired shape, and of course, the sheet 7 must correspond in size and shape thereto. 55

The advantages of my invention are that the plate sinking sheet being transparent, the picture or print upon the paper to be embossed is visible at all times, and can be accurately centered, and is securely held in 60 correct position between the sheet 3 and the frame 6 so that it cannot slip and become displaced during the operation of embossing. It is also inexpensive to make and easy and 65 simple to use.

What I claim and desire to secure by Letters Patent is:

A plate sinking die comprising a frame having a die opening therein, a carrier sheet overlying the front face of said frame and 70 extending over said opening, means uniting the carrier sheet and frame at one end so that they may be separated at the other end, and a die block secured to the back of said carrier sheet in a position to be normally 75 maintained in said opening by said sheet, so that when a piece of work is interposed between the frame and the carrier sheet, it may be embossed by said die block upon the application thereto of extraneous pressure, said die block and carrier sheet being transparent so that the work may be visible to the operator while being placed in position between the carrier sheet and the frame. 80

In testimony whereof I have hereunto set 85 my hand this thirtieth day of September, 1925.

JOSEPH R. THONET.
